(57) **CLAIM**

The ornamental design for a combination bottle and threaded nipple brush with base, as shown and described.

DESCRIPTION

FIG. 1 is an exploded front perspective view of the combination bottle and threaded nipple brush with base per this invention;

FIG. 2 is an exploded front elevation view thereof;
FIG. 3 is a front elevation view of the combination bottle and threaded nipple brush with base of FIGS. 1-2, but being shown fully assembled, the rear elevation view and the side elevation views appearing the same;

FIG. 4 is a top plan view thereof;

FIG. 5 is a bottom plan view thereof;

FIG. 6 is a front elevation view of the base component, shown separately for clarity of appearance, the rear and side elevation views appearing the same;

FIG. 7 is a top plan view of the base component thereof;
FIG. 8 is a top perspective view of the base component thereof;

FIG. 9 is a bottom plan view of the threaded nipple brush component, shown separately for clarity of appearance;

FIG. 10 is a front elevation view of the threaded nipple brush component, the rear and side elevation views appearing the same;

FIG. 11 is a top plan view of the threaded nipple brush component; and,

FIG. 12 is a top perspective view of the threaded nipple brush component.
